UNITED STATES PATENT OFFICE.

WILLIAM J. GROTHUIS, OF CHICAGO, ILLINOIS, ASSIGNOR TO BIFLEX PRODUCTS COMPANY, OF WAUKEGAN, ILLINOIS, A CORPORATION OF ILLINOIS.

AUTOMOBILE BUMPER.

1,413,220.

Specification of Letters Patent. Patented Apr. 18, 1922.

Application filed August 24, 1921. Serial No. 495,019.

To all whom it may concern:

Be it known that I, WILLIAM J. GROTHUIS, a citizen of the United States, and a resident of Chicago, in the county of Cook and State of Illinois, have invented certain new and useful Improvements in Automobile Bumpers, of which the following is a specification.

This invention relates to improvements in bumpers, and more particularly to bumpers of the so-called resilient bar type, such as disclosed in Letters Patent No. 1,374,893, granted to William G. Pancoast and myself on April 12, 1921.

The object of the present invention is to provide an improved or modified construction of the bumper directed more especially to the treatment of the bars forming the bumper structure, whereby a greater degree of rigidity and stiffness is afforded, to the end that a greater impact may be received without injury to the bumper or the vehicle on which it is mounted. The novel features will be more readily understood from the detailed description which follows, and in connection with the accompanying drawings which may be briefly described as follows:

Fig. 1 is a top plan view of the bumper attached to a vehicle,

Fig. 2 is a view in front elevation of the bumper,

Fig. 3 is an enlarged detailed view of one end portion of the bumper,

Fig. 4 is a detailed view in rear elevation as taken on line 4-4 of Figure 3,

Fig. 5 is a detailed view in cross-section taken on line 5-5 of Figure 3,

Fig. 6 is a top plan view showing the use of a collar as a modification of the slot and pin connection between the members, and

Fig. 7 is a view in vertical section taken on line 7-7 of Figure 6.

A bumper embodying the features of the present invention, consists of a structure made up of bars of metal having an inherent degree of resiliency, these bars being arranged so as to be yieldable in a horizontal direction, and comparatively non-yieldable in a vertical direction. In general, the bumper structure comprises an impact section, preferably consisting of a single bar 2 extending throughout the entire length of the bumper, and provided intermediate its ends with a centrally disposed offset portion

3 which forms, together with a short bar 4 having an identical offset portion, a central impact area of increased width. As clearly shown in Figure 2, the short bar 4 is provided at its ends with straight portions 4^a-4^a, which bear flatwise against the bar 2 immediately beyond the ends of the offset portion 3 thereof, and these overlapping portions are secured together by means of collars 5-5 which clamp the parts together. The ends of the bar 2 are bent rearwardly and inwardly in U-shape, forming the ends of the bumper structure, and terminating in comparatively short end sections 6-6. Spaced rearwardly of the front bar 2 is a rear or secondary bar 7 extending parallel thereto throughout its central portion, and inclined forwardly, meeting the ends of the end sections 6-6 in flatwise contact. The end portions of said bar 7 are curved forwardly and inwardly in the form of substantially semi-circular portions 8-8 extending from the ends of the end sections 6-6 in a general transverse direction to the front bar 2, the extremities bearing flatwise, against said front bar at points inwardly disposed from the ends of the bumper, and fixed thereto by means of rivets 9-9.

The structure thus described is adapted to be attached to the forward end of a motor vehicle, and more especially to the forward ends of the longitudinal frame members 10-10 of the vehicle, there being employed for this purpose attaching brackets 11-11 adapted to be fixed to the frame members, and directly connected to the rear bar 7 immediately adjacent its ends, and inwardly from the free ends of the end sections 6-6 of the front bar 2.

Referring to Figure 3, the structure above described is shown in detail. As before suggested, the rear bar 7 has flatwise contact with the end sections 6-6 at the free ends thereof, and is extended beyond in the semi-circular curved portions 8-8 and fixed to the front bar 2 immediately forward of said free ends. As hereinbefore described, the rear bar 7 and front bar 2 of the impact section are further connected at the points of overlapping or flatwise contact between the free ends of the end sections 6-6 and said rear bar 7, adjacent the inner end of the curved portions 8-8 thereof, and preferably in the following manner: Rivets 12-12 are

inserted through the rear bar 7 at the points of connection, these rivets projecting rearwardly and through longitudinal elongated slots 13-13 formed in the free ends of the 5 end sections 6-6 of the front bar 2. These rivets are formed with a cylindric shank which engages the slot and a head at the outer ends of the shank; thus a secure, yet 10 yieldable connection is made, permitting a limited longitudinal movement between the connected parts. Normally, the rivets engage the central portion of the slots, thus 15 permitting a yielding movement in either direction. Manifestly, such a connection is desirable, inasmuch as it increases the flexibility of the structure under impact, and particularly blows received at the ends of the bumper either from the front or rear.

In Figures 6 and 7 is illustrated modification 20 of the construction just described; namely, a fitting in the form of a collar 15 clamped to the rear bar 7 and having a recessed portion 16 extending over and enclosing the free ends of the end sections 6-6. Thus, as before, the bars are retained in flatwise contact, although relative sliding movement therebetween is permitted. A further 25 departure is shown in Figure 6; namely, the use of a single collar 17 which surrounds and 30 clamps the ends of the bars 4 and 7 to the front bar 2, thus eliminating the rivets 9-9 of Figure 3.

Having described in detail a preferred construction for a bumper, the more important features thereof, and the advantages derived therefrom, will now be considered. The rear bar 7 extending parallel to the front or impact bar provides a secondary or reinforcing member therefor. Furthermore, 40 this rear bar has direct connection with the vehicle frame through the medium of the attaching brackets 11-11, and acts in the nature of a brace between these brackets, as well as the supporting member for the impact 45 portion of the bumper. It is to be particularly observed that this rear bar terminates short of the ends of the bumper, the ends thereof being bent forwardly and rigidly secured to the front or impact member of the 50 bumper on either side of the central impact area of increased width, this part of the bumper, including said rear bar and the central impact area, forming in effect a complete structure, quite independent of the end 55 sections of the bumper, and by reason of its comparatively short length and conformation of the end portions of the rear bar, forms a very strong, yet resilient frame, giving the maximum protection against blows received 60 centrally of the bumper and directed toward the more vital parts of the vehicle. In order to increase the resistance to impacts transmitted throughout this central structure, the semi-circular end portions 8-8 of the rear 65 bar are preferably stiffened by the formation

of a rib and complementary groove extending longitudinally between the upper and lower edges of these portions of the bar, as shown at 18 in Figures 4 and 5.

By reason of this construction, it follows 70 that the U-shaped end portions of the bumper are, as a matter of fact, lateral extensions of the front bar rather than intermediate sections between the front bar and the rear bar, through which all shocks received by the bumper through the end sections are transmitted. On the other hand, impacts received at the ends of the bumper are transmitted partially through the end portions 8-8 of the rear bar 7, and partially 80 absorbed within the V-shaped end portions 6-6 through the yieldable connections between the free ends of said end sections and the rear bar in the form of the so-called pin and slot connection, or its equivalent. Moreover, 85 this yieldable connection functions regardless of the direction in which the ends of the bumper are struck. For instance, the vehicle, in backing up, will often engage an obstruction tending to bend the end sections 90 of the bumper in a forward direction. Clearly, a strain upon a bumper of this character will be yieldably resisted in the same manner that an impact delivered against the end sections from the front or side, is resisted.

Having described the novel features of a bumper embodying the invention, and several of the advantages thereof, what I claim as new and novel is:

100

1. A bumper comprising an impact bar having U-shaped end portions terminating in free ends, a bar spaced rearwardly of said impact bar, and having its ends bent forwardly and inwardly, engaging the free 105 ends of said impact bar and connected to the forwardly disposed portion thereof.

2. A bumper comprising an impact bar having its end portions bent rearwardly and inwardly, a bar spaced rearwardly from said impact bar and extending between and beyond the free ends thereof, and terminating in U-shaped end portions engaging said impact bar, and means for connecting said bars adjacent their free ends.

115

3. A bumper comprising an impact bar having its end portions bent rearwardly and inwardly, a bar spaced rearwardly from said impact bar, and terminating in U-shaped end portions extending forwardly and inwardly, and means for connecting said bars together at their free ends, one of said connections permitting limited endwise movement between said bars.

120

4. A bumper comprising an impact bar 125 having its ends bent rearwardly and inwardly to form U-shaped free end portions, a bar spaced rearwardly of said impact bar and having its ends bent in U-shape and having overlapping engagement with said 130

impact bar at the free ends and intermediate the end portions thereof, said bars being connected together at their respective free ends.

5. A bumper comprising an impact bar bent in U-shape at its ends, a bar spaced rearwardly of said impact bar and having its ends bent forwardly and inwardly, and fixed at its ends to said impact bar intermediate the ends thereof, and bumper supporting members engaging said rear bar.

6. A bumper comprising an impact bar having its end portions bent rearwardly in U-shape, a bar extending longitudinally between the free ends of said impact bar, and having overlapping engagement therewith, the end portions of said last mentioned bar being bent toward and connected to said impact bar, and means for yieldably connecting the ends of the impact bar to said last mentioned bar.

7. A bumper comprising an impact bar having its end portions bent rearwardly in U-shape, a bar extending longitudinally between the free ends of said impact bar and having its end portions bent forwardly and fixed to said impact bar, said free ends of the impact bar being loosely connected to said last mentioned bar.

8. A bumper comprising an impact bar having its ends bent rearwardly and inwardly to form the end portions of the bumper, a bar spaced rearwardly from said impact bar, and having overlapping engagement with the free ends thereof, the end portions of said last mentioned bar being bent forwardly and inwardly and fixed to said impact bar, and means for connecting the overlapping portions of said bars, and adapted to permit relative movement therebetween.

9. A bumper comprising an impact bar having end portions bent rearwardly and inwardly to form the end portions of the bumper, a bar spaced rearwardly from said impact bar and having its end portions bent forwardly and inwardly in U-shape, and fixed to said impact member inwardly from the ends of the bumper, the free ends of the impact bar having flatwise contact with said

rear bar, and means permitting a limited longitudinal sliding movement between the contacting parts of said bars.

10. A bumper comprising an impact bar having its ends bent rearwardly and inwardly to form the end portions of the bumper, a bar spaced rearwardly from said impact bar and having its ends bent forwardly and fixed to said impact member inwardly from the ends of the bumper, the free ends of the impact bar having flatwise contact with said rear bar, and a longitudinal slot and pin connection therebetween.

11. A bumper comprising an impact bar having its end portions bent rearwardly and inwardly in U-shape, a rear bar extending parallel to said impact bar, and having its end portions bent forwardly and inwardly, the free ends of each bar being connected to the other bar in overlapping engagement therewith, there being provided limited endwise movement between said bars at the free end of said impact bar.

12. A bumper comprising an impact bar, having its end portions bent rearwardly and inwardly in U-shape, a rear bar extending parallel to said impact bar and having forwardly extending end portions, the free ends of said bars being connected with the other bar short of the ends of the bumper, and one of the connections being yieldable to permit the longitudinal movement of the free end of the bar there connected.

13. A bumper comprising an impact bar having its end portions bent rearwardly and inwardly, a bar spaced rearwardly of said impact bar, the end portions thereof being yieldably connected with the ends of said impact bar, and extended forwardly beyond the points of yieldable connection, and connected at its ends to said impact bar intermediate the end portions thereof, and clamping members adapted to engage said rear bar intermediate its end portions for attaching the bumper to a vehicle frame.

In witness whereof, I hereunto subscribe my name this 18th day of August, A. D. 1921.

WILLIAM J. GROTHUIS.
